(57) **CLAIM**

The ornamental design for jewelry article string with lucky charm, as shown and described.

DESCRIPTION

FIG. 1 is a front view of the jewelry article;
FIG. 2 is a left side view of the jewelry article;
FIG. 3 is a rear view of the jewelry article;
FIG. 4 is a right side view of the jewelry article;
FIG. 5 is a top view of the jewelry article;
FIG. 6 is a bottom view of the jewelry article;
FIG. 7 is a perspective view of the jewelry article;
FIG. 8 shows the jewelry article of FIGS. 1-7 with the button-like semispherical element introduced into the buttonhole of a men's suit, with the decorative pendent portions visible out of the pocket; and,
FIG. 9 shows the jewelry article of FIGS. 1-8 with the string and the pendent part completely located into the pocket of the men's suit.
The broken line showing of a man's jacket is for illustrative purposes only and forms no part of the claimed design.
